UNITED STATES PATENT OFFICE.

HERBERT W. MERRILL, DECEASED, BY ANNA M. MERRILL, ADMINISTRATRIX, OF SAGINAW, AND GEORGE P. MERRILL, ADMINISTRATOR, OF SAGINAW, MICHIGAN.

MACHINE FOR MAKING WOOD FIBER.

Application filed October 24, 1919. Serial No. 332,861.

To all whom it may concern:

Be it known that we, ANNA M. MERRILL, administratrix, and GEORGE P. MERRILL, administrator, of the estate of HERBERT W.

5 MERRILL, deceased, citizens of the United States, both residing at Saginaw, in the county of Saginaw, State of Michigan, have become possessed of certain new and useful Improvements in Machines for Making 10 Wood Fiber, the same being the invention of the said HERBERT W. MERRILL, late of Saginaw, Michigan; and we do hereby declare the following to be a full, clear, and exact description of the invention, such as 15 will enable others skilled in the art to which it appertains to make and use the same.

This invention relates to machines for making wood fiber and pertains more particularly to an improved cutter head adapted 20 to manufacture fiber from waste slabs and edgings by progressively removing the surface of the material in shreds or fibers as it passes the cutter, the movement of the material being lengthwise its grain.

25 In the manufacture of wood fiber to be used as a substitute for hair in the making of mortar for plastering and similar work, it is essential that the fibers be of substantially uniform thickness and long, with as 30 small a percentage as possible of broken fibers.

It is also desirable that a machine for making such material shall be capable of being readily adjusted so as to produce 35 fibers of greater or less thickness as may be desired.

The objects of my improvement are, first, to provide a cutter head of simple and durable construction that will produce long fibers 40 of substantially uniform thickness; second, to provide a cutter head capable of being readily adjusted to produce fibers of size and length as desired; third to so construct the knives that they will be capable of being 45 easily and quickly sharpened by grinding without more labor than is ordinarily required to sharpen a common flat knife.

A further object is to so form the cutting edge of the knife that its teeth or cutters 50 will retain their shape after repeated grinding.

With these and certain other objects in view, which will appear later in the specifi-

cation, my invention consists of the devices described and claimed and the equivalents 55 thereof.

In the drawings, Fig. 1 is an end view of a cutter head with its knives attached.

Fig. 2 is a plan view of part of a knife.

Fig. 3 is a plan view broken away in part, 60 showing a modified form of knife.

Fig. 4 is a diagrammatic view showing the relative working positions of the cutting edges of three successive knives.

Fig. 5 is a detail view showing the fibers 65 in the finished product.

Fig. 6 is a perspective view of a board or slab, showing the appearance of its scored surface, after having passed the knives.

Fig. 7 is a part sectional side view of a 70 knife, indicating by dotted lines the manner of sharpening.

As is clearly shown in the drawings, the knife consists in a cutter head 1 of any suitable or usual construction, a hexagonal head 75 being shown for purpose of illustration.

2 is the journal of the cutter head and 3 the knives, which are provided with fastening devices, by which the knives are secured to the cutter head. These fastening devices 80 may be of any suitable construction, as for illustration, the slotted holes 3^a, which may be formed in the knife, to receive the screws 4.

The edge of each knife is formed with a plurality of teeth produced by cutting serrations 6 along the edge of the knife, as 85 shown in Figs. 3 and 7. These serrations extend from the front or advancing face of the blade backward to the rear face 3, as shown by the dotted line at 12 in Fig. 7. 90

The knives are mounted on the cutter head 1 in substantially the relation shown diagrammatically in Fig. 4, where 7, 8 and 9 represent the relative positions of the cutting edges of three successive knives on the 95 cutter head. It will be noted that the points of the teeth of successive knives are slightly offset with relation to each other, so if a given number of knives, say n , are used, each knife will be offset with respect to the other 100

knives, making a cycle of $\frac{1}{n-1}$ of the spacing of the points of the teeth. One or more cycles can be completed at each revolution of the cutter head.

105 As the board passes the cutter head in the

manner commonly employed in planers and other wood working machines, the surface of the board is scored by the teeth 6 of knife 7, so that the points of successive knives 5 separate the wood into its fibers and loosen the fibers by successively crowding them sidewise, as distinguished from the action of knives in excelsior and shaving machines, by which pieces of wood are merely cut or 10 chipped off from the material. The scoring action herein referred to is similar to the scoring produced by a sharp scratch awl, the point of which is repeatedly inserted in closely adjacent position into the surface of 15 the wood and then drawn along the face of the material in a direction substantially parallel with the grain of the wood. I therefore produce long slender somewhat hair-like fibers which are suited for use as substitute 20 for hair in plastering, structural work, etc. The teeth of blade 8 follow immediately the cut of blade 7, but being slightly offset with relation to the teeth of blade 7, score the surface of the material in different places and 25 loosen the fibers of the board between the scores. Similarly, a further scoring of the surface is made by blade 9, the effect being when the cutter head is rapidly rotated, to quickly shred the surface of the material 30 and to produce a large quantity of fibers of substantially uniform size and comparatively long, as indicated diagrammatically in Fig. 5.

To provide for easily and quickly grinding the knives without altering the shape of 35 the teeth, I arrange the serrations as shown in Fig. 7, and as previously described, so that the grinding wheel when passed along

the surface of the knife will remove the metal, as shown at 10, Fig. 7, and the second 40 grinding will further remove the metal as shown at 11. This process may be repeated until the knife is worn out without changing the shape of the cutting teeth.

By the means above described, I have produced a cutter that is capable of producing fibers of substantially uniform size and comparatively long, and at a high rate of speed. No especially skilled labor is required to make the adjustments by which finer or 50 coarser material is produced, and the knives can be sharpened by anyone who can sharpen a plain flat knife.

Having thus described my invention, what we claim and desire to secure by Letters 55 Patent is:

In a wood fiber cutting machine, the combination with a cutter head, knives mounted thereon, each knife having its cutting edge provided with teeth forming sharp scoring points, the scoring points of one knife being offset sidewise with relation to the scoring points of the next knife, the amount of offset being only slightly in proportion to the width of the scoring point, whereby the wood 60 scored by the teeth of one knife is successively sheared by the succeeding slightly offset knives, to produce long hair-like fibers, substantially as described.

In testimony whereof we affix our signatures.

ANNA M. MERRILL,
Administratrix.

GEO. P. MERRILL,
Administrator.
